UNITED STATES PATENT OFFICE.

LEE ANDREW TETER, OF CANTRIL, IOWA.

SILAGE-PACKER.

1,279,938.

Specification of Letters Patent. Patented Sept. 24, 1918.

Application filed December 7, 1917. Serial No. 206,016.

To all whom it may concern:

Be it known that I, LEE A. TETER, a citizen of the United States, residing at Cantril, in the county of Van Buren and State of 5 Iowa, have invented new and useful Improvements in Silage-Packers, of which the following is a specification.

This invention relates to new and useful 10 improvements in ensilage packing devices for silos and the principal object of the invention is to provide a device including rollers for traveling over the ensilage and supporting an engine for driving the device and adding to the weight thereof to increase the 15 packing effect.

Another object of the invention is to provide an automatically adjustable roller for packing the ensilage adjacent the silo wall which is out of the path of the main rollers.

20 A further object of the invention is to provide means for adjusting the position of the conical roller to accommodate the device to different sizes of silos.

Another object of the invention is to provide 25 a device of this character which is simple and durable in construction, reliable and efficient in operation and one which can be manufactured and placed upon the market at a minimum cost.

30 The invention also consists in certain other features of construction and in the combination and arrangement of the several parts, to be hereinafter fully described, illustrated in the accompanying drawings and 35 specifically pointed out in the appended claims.

In describing my invention in detail, reference will be had to the accompanying drawings wherein like characters denote like 40 or corresponding parts throughout the several views, and in which:

Fig. 1 is a plan view of the invention.

Fig. 2 is an elevation thereof.

Fig. 3 is a view of the front or small end.

45 Fig. 4 is a cross section on line 4—4 of Fig. 1 showing the means for adjusting the conical roller.

Fig. 5 is a detail showing one of the brackets engaging with the packing roller.

50 Fig. 6 is a view of the rear end.

As shown in these views the frame of the device is composed of two elongated bars 1 slightly convergent and having their front ends connected together by a block and their 55 rear ends bolted to a bolster 2, said bolster extending beyond each of said bars. The

frame is provided with a platform 3 on which is located a motor 4 and the bearings 5 for the shafts 6 and 7. As shown the two shafts are connected together by the beveled gears 8 and the shaft 6 carries the toothed wheel 9 which is connected with the driving wheel of the motor by the gear 10. The other shaft carries a toothed wheel 11. 12 indicates the guiding roller which is of conical shape and which is mounted in the bearings 13 and 14 depending from the bottom of the frame. This roller carries a toothed wheel 15 and a chain 16 passes over this wheel and the wheel 11 whereby the 15 guiding roller will be rotated from the motor. 17 indicates small wheels for tightening the chain. The bearing 14 is movable so as to adjust the position of the small end of the guiding roller. As shown this bearing is formed on a bell crank lever 18 which is pivoted to a support 19 and the end of this support is rounded to permit the axle of the roller to have movement about the same. 20 are strips located on the roller for providing 25 a gripping surface thereon. To the underside of the bolster 2 is secured a number of brackets 21 having notches 21' formed in their lower depending ends. 22 is the packing roller provided with the shaft 23 which 30 engages with the notches 21' in the brackets. As shown the roller is made up of a plurality of roller elements 24, said elements being located between the brackets as shown. 25 is a small roller carried by the projecting 35 bars 26 on the end of the frame and adapted to engage with the walls of the silo to prevent the device from contacting therewith. 40 It will be seen that a space will be left adjacent the walls of the silo which will not 45 be packed by the rollers and to provide means for packing this strip I employ a narrow roller 27 carried by a bar 28 which is 50 slidably carried by the brackets 29 on the frame. The outer end of said bar, which 55 carries the roller, is bent to throw the roller wheel beyond the frame and a supporting bar 30 is secured to this bar adjacent the roller and has its other end pivoted in a bracket 31 carried at the end of the frame. 60 To hold the roller 27 in its outermost position where it will engage with the material adjacent the walls of the silo I provide a spring 32 engaging a roller 32' on the bar 28 carrying the roller and having its other 65 end bearing against a bracket 33 located on the frame. It will thus be seen that this 70

spring tends to move the bar longitudinally to throw the wheel 27 against the wall of the silo.

When the device is placed in the silo and assembled and the motor started the guiding wheel will be rotated and thus cause the device to be moved in a circle within the silo and by adjusting the inner end of said wheel the device may be caused to move in circles 10 of varying diameters.

It is thought from the foregoing description that the advantages and novel features of my invention will be readily apparent.

What I claim is:—

15 1. A device of the class described comprising a frame, a conical guiding roller

thereon, a packing roller extended at right angles to the conical roller, means for rotating the rollers and means for adjusting the position of the guiding roller on the 20 frame for guiding the device in different sizes of circles.

2. A device of the class described comprising a frame, guiding and packing rollers carried thereby, means for adjusting one 25 end of the guiding roller, a second packing roller, a longitudinally movable shaft carrying the same and a spring engaging with said shaft and tending to move the same outwardly.

30 In testimony whereof I affix my signature.

LEE ANDREW TETER.
